(57) **CLAIM**

The ornamental design for a domed cat litter box, as shown.

DESCRIPTION

FIG. 1 is a perspective view of the front and right side of a domed cat litter box showing our new design;

FIG. 2 is a front elevational view thereof;

FIG. 3 is a right side elevational view thereof, the left side being a mirror image;

FIG. 4 is a rear elevational view thereof;

FIG. 5 is a top plan view thereof;

FIG. 6 is a bottom plan view thereof;

FIG. 7 is a rear view of the dome top thereof;

FIG. 8 is a front view of FIG. 7;

FIG. 9 is a perspective view of FIG. 7;

FIG. 10 is a left side view of FIG. 7;

FIG. 11 is a rear perspective view of FIG. 7;

FIG. 12 is a side view of the base;

FIG. 13 is a cross-sectional view taken along line 13—13 in FIG. 12;

FIG. 14 is a top view of FIG. 12; and,

FIG. 15 is a perspective view of FIG. 12.

The broken lines in FIGS. 2-11 are for illustrative purposes only and form no part of the claimed design.
